UNITED STATES PATENT OFFICE.

EDWARD C. FREMAUX, OF RAYNE, LOUISIANA.

AUTOMATIC CUT-OFF AND FILTER.

SPECIFICATION forming part of Letters Patent No. 562,718, dated June 23, 1896.

Application filed July 6, 1895. Serial No. 555,130. (No model.)

To all whom it may concern:

Be it known that I, EDWARD C. FREMAUX, of Rayne, in the parish of Acadia and State of Louisiana, have invented a new and Improved Automatic Cut-Off and Filter, of which the following is a full, clear, and exact description.

This invention relates to devices for discharging rain-water from a roof into a cistern or similar receptacle, the object being to provide a device whereby the initial flow of water from a roof, at the beginning of a rain-storm, will be directed to the ground outside the cistern, thus preventing dirt and impurities that may have gathered on the roof during a long dry spell from entering the cistern, and then, after the roof shall have been thoroughly cleaned or washed, to direct the water into the cistern.

With this end in view the invention consists in a receiver attached to the lower end of a water-leader, and comprising two legs or members, one of which is extended into the cistern and the other directed to the outside thereof, and having means for automatically changing the direction of the water flow.

It further consists in the construction and novel arrangement of parts, as will hereinafter appear, and be more particularly pointed out in the appended claim.

Reference is to be had to the accompanying drawings, forming a part of this specification, in which similar characters of reference indicate corresponding parts in all the figures.

Figure 1 is a side elevation of a cut-off and filter embodying my invention. Fig. 2 is a front elevation of the same. Fig. 3 is a vertical section showing one position of the cut-off valve. Fig. 4 is a similar section, but showing the valve in a reverse position; and Figs. 5 and 6 show modifications.

Referring by the reference-characters to the drawings, A designates the shell or casing, comprising two legs or members A' A², communicating through ducts a a' with the mouth a², into which the water spout or leader a³ extends.

The legs A' A² are sufficiently separated to allow the device to be placed and secured on the wall of a cistern or other receiver X, with one leg, A', inside the cistern and the other leg, A², outside thereof.

B is the shifting valve, consisting of a plate of suitable material, mounted on a rock-shaft b, having bearings in the opposite side walls 55 of the shell or casing A at the apex of the inclined bottoms of the ducts a a'.

B' is the valve-shifting device, consisting of a tube or bucket engaging around and adapted to slide vertically on the leg A². The 60 lower end of the bucket B' has a perforation in it, and in the perforation I place a sponge b' or similar material. The bucket B' has upwardly-extending plates b², movable in guide-ways b³, secured to the opposite sides of the 65 shell or casing A, and coiled springs B² are connected at one end to lateral projections b⁴ on the bucket and at the other end to lateral projections b⁵ at the upper end of the guide-ways b³.

The rock-shaft b at each end is turned at substantially right angles to the body portion of the shaft, forming arms b⁶, which engage between pins b⁷, extended outward from the plates b².

The bottom wall of the duct a' is extended across the leg A², and an opening c is formed in such extended portion, through which water may flow to the bucket B'. To prevent vegetable matter or other such substances 80 that may be washed off a roof from passing through the opening c, I place a wire screen or netting C over the same, and as a means for regulating the size of the opening c I employ a slide-plate C', movable beneath the 85 screen C and having an opening through it corresponding in size to the opening c.

The walls of the leg A' at their lower portion are provided with perforations c', and the leg is provided with a removable bottom 90 closure c², which also may be perforated. Within the leg A' is a filtering material C², such, for instance, as charcoal, but I do not limit the invention to any particular filtering material. If desired, a perforated plate c³ 95 may be removably placed on the filtering material.

The operation of the device is as follows: The normal position of the valve B, or during dry weather, is as shown in Fig. 3. When a 100 rain-storm commences, the greater part of the water from the roof will at first discharge through the duct a' to the ground, carrying with it the dirt and other refuse that may be

on the roof. A small portion of the water will enter the bucket B' through the opening c, and when a sufficient weight or amount of water shall have entered the bucket to overcome the resistance of the springs B² the bucket will be forced downward, thus rocking the shaft b and shifting the valve B to the position shown in Fig. 4, and then of course the water will filter through the material C² into the cistern. As the water is running into the cistern, the sponge b' in the bottom perforation of the bucket B' will allow a very gradual discharge of water from the bucket, so that the springs may draw the bucket upward and shift the valve to its normal position. The discharge from the bucket is designed to be very slow, so that the valve will not be returned to its normal position until the rain shall have ceased, but if the rain-storm were a prolonged one the weight of water flowing over the valve through the duct a would have a tendency to hold the valve in that position even though the water be all discharged from the bucket.

The inflow of water to the bucket may be regulated by setting the slide-valve C', so that the washing process of a roof may be continued for a greater or less length of time, and by means of the valve C' the device may be adapted for large or small roofs, that is, when the device is attached to the water-leader of a large roof, the valve should be moved to restrict the passage to the bucket, so that a large mass of water may pass off before filling the bucket. When the roof is small, the opening c may be opened to its full capacity. This valve, however, should be adjusted by the workman applying the device, as he in most cases will be able to judge of the size of the opening required.

In the examples of my improvement shown in Figs. 5 and 6, I have shown slight changes

in the form of the upper portion of the shell to adapt the device to roofs having but slight pitch and also to accommodate it to cisterns 45 that reach to or nearly to the eaves of a roof.

In Fig. 5 the entrance end D and the end D', discharging into the cistern, are in the same substantially horizontal plane, and communicating with these parts is the vertical leg D², 50 on which the bucket B' moves, as in the first example of my improvement. The valve B is in position to allow the discharge of water and dirt through an opening in the side d, until sufficient water shall have entered the bucket 55 to shift the valve to close said outlet, and then the clear water will discharge into the cistern through the filter.

In Fig. 6 the water from the house-pipe enters at D³ and first discharges to clean the 60 roof through an opening in the side d', and after shifting the valve the water will discharge into the cistern through the part D⁴, which is at a slight downward angle to the part D³.

It will be seen that my device is wholly automatic in its operation, so that no attention is required from the occupants of a house.

Having thus fully described my invention, I claim as new and desire to secure by Letters 70 Patent—

In a device of the class described, a shell or casing comprising two outlets for water, the walls of one outlet being provided with perforations, a perforated removable bottom 75 closure for the outlet, a filtering material in said outlet, a valve, and the gravity-bucket for operating the valve, substantially as specified.

EDWARD C. FREMAUX.
